UNITED STATES PATENT OFFICE.

WILLIAM ADAMS, OF AKRON, OHIO.

ELECTRIC SWITCH.

Application filed September 17, 1923. Serial No. 663,102.

To all whom it may concern:

Be it known that I, WILLIAM ADAMS, a citizen of the United States, residing at Akron, in the county of Summit and State of Ohio, have invented certain new and useful Improvements in Electric Switches, of which the following is a specification.

This invention relates to an improved electric switch which is especially, but not necessarily, adapted for use in connection with motion and direction signals for motor vehicles.

It is my aim to generally improve upon devices of this class by providing one of comparative simplicity and durability wherein the parts are arranged in a novel manner to produce an exceedingly practical structure highly desirable for the particular purpose specified.

Other objects will appear as the nature of the invention is better understood, and the same consists in the novel form, combination, and arrangement of parts, herein-after more fully described, shown in the accompanying drawings, and claimed.

In the drawings, wherein like reference characters indicate corresponding parts throughout the several views:

Figure 1 is a top plan view of an electric switch constructed in accordance with the present invention.

Fig. 2 illustrates the switch shown in Fig. 1 with the upper casing section thereof removed, and also diagrammatically illustrating the electrical wiring system employed in conjunction therewith.

Figure 3 is a longitudinal sectional view taken substantially upon the line 3—3 of Figure 2.

As shown, the invention embodies the provision of a special form of switch embodying a casing composed of an upper section 5 and a lower section 6, which, when assembled, completely encloses the mechanism to be described, except turnbuttons 7 and 8, which are used to properly operate the switch. The enclosure of the mechanism absolutely insures the desired results by eliminating any difficulties arising from exposure of the mechanical parts. The purpose of this switch is to operate two signal lights.

As shown better in Figures 2 and 3, the switch embodies a pair of transversely arranged rollers 17 and 18 which are respectively adapted to be turned by the handles

or turn buttons 7 or 8, said rollers being journaled in the lower section 6 of the case in the direction indicated by the arrows in Figure 3.

The roller 17 has two ratchet-like indentations 19 and 20, and one portion thereof between said notches is flattened as indicated at 21. As shown in Figure 3, the roller 17 is in neutral position and is held in that position by means of three pieces of spring brass 22, 23 and 24, or other satisfactory metal, which are fastened to a partition 25 that is fixed to the casing section 6 midway between the rollers 17 and 18. A metal conducting strip 26 is secured upon the flat portion 21 of the roller 17 in position to bridge the strips or contacts 22 and 23, and a further conducting strip 27 is fastened upon the notched portion 20 of said roller in position to bridge the contacts 23 and 24.

In a like manner, the roller 18 is provided with ratchet-like indentations 28 and 29, while a portion of the roller between said indentations 28 and 29 is flattened as indicated at 30. As shown in Figure 3, the roller 18 is in neutral position and is held in that position by the spring contacts 22 and 23 and a further spring contact 31 that is fastened to the partition 25 in alignment with the contact 24, but insulated from the latter. The flattened portion 30 of the roller 18 carries a conducting strip 32 that is arranged to bridge the adjacent ends of the contacts 22 and 23, and a further conducting strip 33 is fastened upon the ratchet shaped indentations 29 in position to bridge the contacts 23 and 31.

As shown in Figure 2, the electric light bulbs 9 of both signal lights are connected by means of a wire 34 with the contact 22, and the contact 23 is connected by means of a wire 35 with a suitable source of electricity 36, which may consist of the battery usually found upon motor vehicles, one terminal of which is grounded as at 37 to receive the current from the grounded terminals 38 of the lamp 9.

A wire 39 connects the contact 24 with the lower lamp 10 of the left turn signal, and a wire 40 similarly connects the contact 31 with the lower lamp 10 of the right turn signal.

If the driver wishes to make a left turn and to indicate this fact with the construction above described, the turn button 7 is

rotated to the left until the conducting strip 26 bridges the contacts 22 and 23. When this is done, the electric current travels from the battery 36 to a contact 23, through strip 26 to contact 22 and then through wire 34 to both lamps 9, whereby the latter are both displayed. Owing to the fact that both lamps 9 are simultaneously displayed at this time, they will serve as a warning to every one concerned, both in the front and rear of the vehicle, that a change in course of travel is about to be made.

After this warning has been given, the operator continues to turn the turn button 7 to the left, which results in extinguishing the lamps 9 and allows the contacts 22, 23, and 24 to drop into the notch 20 so that the strip 27 will bridge the contacts 23 and 24. With the roller 17 in this position, the current flows to the contact 23 through strip 27 to contact 24 and then through wire 39 to the lamp 10 of the left turn signal lamp. After the left turn has been completed, the turn button 7 is again turned to the left, which causes the contacts 22, 23 and 24 to drop into the notch or indentation 19 when the roller 17 is disposed in a neutral position with none of the lamps illuminated.

To indicate a right turn, the operator turns the roller 18 to the right so as to cause the strip 32 to bridge the contacts 22 and 23 for lighting the lamp 9. After the warning is given in this manner, the roller 18 is turned further to the right until the contacts 22, 23 and 31 drop into the indentation or notch 29, whereupon the contacts 23 and 31 will be bridged by the strip 33. The current then flows from the contact 23 to the contact 31 and then through wire 40 to the right turn lamp 10. When the right turn has been made, the turn button 8 is rotated further to the right so as to bring the contacts 22, 23 and 31 into the notch or indentation 28 which has no conducting strip, in which position the lamps will all be unlighted.

Stop and parking signals are displayed by turning either turn button 7 to the left so that contacts 22 and 23 are bridged by the

strip 26, or by turning turnbutton 8 to the right so that said contacts 22 and 23 are bridged by the strip 32. By either operation, both of the upper lamps 9 are simultaneously lighted so as to give notification to all concerned in front, both or either side of the car that the operator intends to stop or is parking. When motor vehicle is again set in motion, if turnbutton 7 is used, it shall be turned to the right so that cross pieces 22, 23 and 24 will rest in the neutral position; and if turnbutton 8 is used, it shall be turned to the left so that cross pieces 22, 23 and 31 will rest in the neutral position. By either of these operations all lights are extinguished.

As the switch is extremely small, it may be conveniently fastened on the instrument board steering column, or at any other location on the vehicle convenient to the operator.

From the foregoing description, it is believed that the construction and operation as well as the advantages of the invention will be readily understood and appreciated by those skilled in the art.

Minor changes may be made without departing from the spirit and scope of the invention as claimed.

What I claim as new is:

An electrical switch comprising an elongated casing, a pair of longitudinally spaced rollers journaled in said casing, separate operating handles for the rollers, said rollers being provided on their surface with circumferentially spaced shoulders and being also provided on their surfaces between the shoulders with movable contact strips, a cross piece in the casing between the rollers, a plurality of spring metal contacts connected to said cross piece and projecting beyond it into the path of the roller, the free ends of said spring metal contacts being successively engageable with the shoulders and movable contacts carried by said rollers.

In testimony whereof I affix my signature.

WILLIAM ADAMS.
